UNITED STATES PATENT OFFICE

131,196

DESIGN FOR A CABINET FOR A LOUD-SPEAKER

Vern Kraus, Cleveland, Ohio

Application July 10, 1941, Serial No. 102,013

Term of patent 3½ years

To all whom it may concern:

Be it known that I, Vern Kraus, a citizen of the United States, residing in the city of Cleveland, county of Cuyahoga, and State of Ohio, have invented a new, original, and ornamental Design for a Cabinet for a Loud-Speaker, of which the following is a specification, reference being had to the accompanying drawing, forming a part thereof.

I claim:

The ornamental design for a cabinet for a loud-speaker, substantially as shown.

VERN KRAUS.
